(57) CLAIM

We claim the ornamental design for a removable guard, as shown and described.

DESCRIPTION

FIG. 1 is a front perspective view of a design of the removable guard;

FIG. 2 is a side elevation view of the removable guard of FIG. 1, with the other sides of the removable guard being identical images thereof;

FIG. 3 is a top plan view of the removable guard of FIG. 1; and,

FIG. 4 is a bottom plan view of the removable guard of FIG. 1.

The portion shown in broken lines is for illustrative purposes only and forms no part of the claimed design.
